PROCESS FOR THE PREPARATION OF
CHOLANIC ACID DERIVATIVES

Temple Clayton, Parsippany, Emanuel B. Hershberg, West Orange, and Bernard Schoen, Union City, N. J., assignors to Schering Corporation, Bloomfield, N. J., a corporation of New Jersey

No Drawing. Application August 19, 1950,
Serial No. 180,506

20 Claims. (Cl. 260—397.1)

1

The present invention relates to the manufacture of intermediates suitable for the preparation of compounds of therapeutic activity, or of compounds which can be converted into substances of therapeutic value, and particularly for the preparation of the compound known as Kendall's Compound E (cortisone).

It is the general object of our invention to provide an improved and simplified procedure for the preparation of 3-hydroxy-12-keto and 3-hydroxy-7,12-diketo cholanic acids of saturated or unsaturated character, whereby the number of steps involved is reduced and likewise the time required, and the yield considerably increased over prior procedures.

A specific object of the invention is to provide a simplified and more efficient process constituting the initial steps in the synthesis of cortisone.

Other objects and advantages of the invention will appear from the following more detailed description thereof.

The process of the present invention is generally applicable for the manufacture of numerically saturated and unsaturated 3-hydroxy-12-keto-cholanic acids, including the $\Delta^{9,11}$ -cholenic acids, wherein a keto group may be present also in the 7-position, whether or not a hydrocarbon group is present between the carboxylic group and the 17-carbon, and thus includes the nor-, bisnor-, and etio-acids. The invention will, however, be further described in detail, and by way of example, in connection with the conversion of desoxycholic and cholic acids into the 3-hydroxy-12-keto and 3-hydroxy-7,12-diketo cholanic acids, but it will be understood that the procedure described can be employed also with the other cholanic and also the cholenic acids to produce analogous products.

In the procedure as described by Kendall (Journal of Biological Chemistry, 73, 271 (1948)) methyl desoxycholate is first prepared from desoxycholic acid in methanol. This ester is then partially benzoylated to protect the 3-hydroxyl, the product is isolated, and thereafter oxidized and again isolated. Since both the methyl desoxycholate and its 3-benzoate carry methanol of crystallization which must be removed before the benzoylation and oxidation, respectively, there are actually no fewer than eight operations involved in this sequence, and the over-all yield is still further adversely affected by failure to remove the last traces of methanol. These intermediate products are, moreover, difficult to crystallize. A better procedure is described by Schwenk et al. (Journal of the

2

American Chemical Society 65, 549 (1943)), who succinylated desoxycholic acid, isolated the half-succinate, and then oxidized it and isolated the 12-keto compound. By this procedure the number of steps was reduced, but the yields were still not entirely satisfactory.

We have found that the acylation of the 3-hydroxyl of the steroid acid can be carried out under conditions such that the reaction mixture containing the 3-ester of the steroid acid can be oxidized directly with chromic acid upon dilution with acetic or other lower aliphatic acid and sulfuric or other strong acid, that is, without prior isolation of the ester, if the reactions occur in the presence of an organic solvent base like pyridine. This was quite unexpected for two reasons. In the first place, pyridine is a relatively oxidizable compound, and its presence in the mixture to be oxidized would therefore be undesirable. In the second place, it is well known that pyridine forms salts with chromic acid, and it was to be expected either that the oxidizing power of the chromic acid would be decreased, or, if the chromic acid should be freed by the sulfuric acid, that then the pyridine would be oxidized. We have, however, found that the oxidation can be made to proceed smoothly and that the crude ketonic product can be isolated in an almost quantitative yield.

The acyl group in the 3-position may be of any suitable type as its function is to protect the hydroxyl group against the oxidizing agent. It may be aliphatic, aromatic, cycloaliphatic or aralkyl in character, and it may be monobasic or polybasic. Examples of satisfactory acyl groups are acetyl, propionyl, butyryl, succinyl, benzoyl, p-methyl benzene sulfonyl, phthalyl, cyclohexylacetyl, etc. In the case of the polybasic acids, the ester will preferably be a partial ester, like a half-succinyl, half-phthalyl, etc.

The following examples illustrate the invention in greater detail but are not to be understood as indicating the scope thereof.

Example 1

A mixture of 19.6 g. desoxycholic acid, 5.25 g. succinic anhydride and 15 cc. anhydrous pyridine was refluxed for one-half hour, and then cooled and diluted with a solution of 9.5 cc. sulfuric acid in 200 cc. acetic acid.

The mixture was further cooled to 13 to 15° C. and to it was added a solution of 3.83 g. CrO_3 in 5 cc. water in two portions. At the end of one hour the temperature was permitted to rise to 15 to 20° for one-half hour and the reaction

mixture was poured into 2.5 l. of water. The white product was collected, washed thoroughly and dried. There was obtained 23.8 g. (97%) of the 12-keto compound, melting from 230 to 235° C.

Example 2

By reactions as described in Example 1, 1176 g. of pure desoxycholic acid, 315 g. succinic anhydride and 900 cc. pyridine were refluxed until succinylation at the 3-position was substantially complete (about 1 hour), and the solution of the half-ester was then poured into 14 liters of acetic acid and oxidized at 20 ± 2 ° C. with 230 g. CrO_3 , 600 cc. concentrated sulfuric acid and 1300 cc. water. After stirring for about two hours, the mixture was cautiously diluted to 100 l. with water, the product was collected on a large filter, washed thoroughly with water and dried at 80° C. The yield was 1330 g. (95% of theory) of white material with specific rotation of a 1% solution in acetone of +96° and melting range from 228 to 232°.

Example 3

By the procedure described in Example 1, using 20.4 g. cholic acid instead of the desoxycholic acid, and oxidizing with 7.7 g. of CrO_3 instead of 3.83 g., and proceeding otherwise as described in such example, the half-succinate of 3-hydroxy-7,12-diketocholanic acid was obtained in good yield.

Example 4

By reactions as described in Example 1, using 5.1 g. acetic anhydride in place of the succinic anhydride and allowing the oxidation to proceed for a total of two hours at 15 to 20° there were obtained 21.1 g. of crude 3-acetoxy-12-ketocholanic acid melting about 180-190°.

Example 5

By the reactions as described in Example 1, using 25 cc. concentrated hydrochloric acid in place of the sulfuric acid, the same 12-keto compound melting at 228 to 234° was obtained in 23 g. yield.

Although we prefer to employ pyridine for providing the basic conditions under which the 3-acylation takes place, other solvent organic bases can be employed, like lutidine, collidine, quinoline, dimethylaniline, etc.

In place of acid anhydride, the acid chloride can also be used to effect acylation. In general, approximately equivalent proportions of the steroid hydroxy acid and of the acylating agent can be employed, but an excess of the latter may be used.

The oxidation of the 3-ester, as shown by the above examples, is carried out without first isolating such ester. While the presence of the sulfuric acid is preferred, other strong acids can be used, such as trichloroacetic, fluorosulfonic, hydrochloric, perchloric, etc. In place of oxidation with chromic acid, other methods of oxidation can be used. In the oxidation of the cholenic acids, the nuclear double bond can be immediately protected in known manner, as by bromination, followed by debromination after the oxidation.

The 3-esters of the cholic and cholenic acids, including their lower homologues or 17-degradation products, can be employed as such in the next step of any desired process, for example to

effect dehydrogenation at C_9 or C_{11} , or they may be saponified in aqueous or alcoholic alkali to restore the 3-hydroxyl.

We claim:

5 1. Process for the manufacture of steroid keto acids, which comprises reacting a member of the group consisting of saturated and unsaturated 3,12-dihydroxy cholic acids in the presence of an organic solvent base with a sufficient amount of a carboxylic acid acylating agent to form the 3-ester, and mixing the entire reaction solution with an oxidizing agent to effect replacement of the 12-hydroxyl with ketonic oxygen.

10 2. Process for the manufacture of steroid keto acids, which comprises reacting a member of the group consisting of saturated and unsaturated 3,12-dihydroxy cholic acids in solution in pyridine with a sufficient amount of a carboxylic acid acylating agent to form the 3-ester, and mixing the entire reaction solution with an oxidizing agent to effect replacement of the 12-hydroxyl with ketonic oxygen.

15 3. Process according to claim 1, wherein the oxidizing agent is chromic acid in acetic acid solution.

20 4. Process for the manufacture of steroid keto acids, which comprises reacting a member of the group consisting of saturated and unsaturated 3,12-dihydroxy cholic acids in pyridine solution with a sufficient amount of a carboxylic acid acylating agent to form the 3-ester, mixing the entire reaction solution with chromic and acetic acids to effect replacement of the 12-hydroxyl with ketonic oxygen, and separating the keto steroid formed.

25 5. Process for the manufacture of steroid keto acids, which comprises reacting a 3,12-dihydroxy cholic acid in pyridine solution with a sufficient amount of succinic anhydride to form the 3-partial ester, mixing the entire reaction solution with chromic and acetic acids to effect replacement of the 12-hydroxyl with ketonic oxygen, and separating the keto steroid formed.

30 6. Process according to claim 1, wherein the cholic acid is cholic acid.

35 7. Process according to claim 5, wherein the cholic acid and succinic anhydride are employed in approximately equimolecular proportions.

40 8. Process according to claim 5, wherein the oxidation mixture is cooled to below room temperature.

45 9. Process according to claim 5, wherein the oxidation mixture is cooled to about 13-15° C.

10. Process according to claim 5, wherein the oxidation mixture, on completion of the oxidation, is poured into water and the precipitated product separated, washed and dried.

11. Process according to claim 5, wherein the oxidation proceeds for about one hour with cooling to about 13-15° C., and for a further half-hour without cooling.

12. Process according to claim 11, wherein the cholic acid is desoxycholic acid.

13. Process according to claim 5, wherein the cholic acid is desoxycholic acid.

14. Process for the manufacture of 12-keto steroid acids, which comprises reacting 1 mole of a 3,12-dihydroxy cholic acid with approximately 1 mole of succinic anhydride in about 300 cc. of anhydrous pyridine under reflux, cooling the reaction solution, adding thereto about 4 liters of acetic acid, cooling the mixture to below room temperature, adding a solution of chromic oxide in water, and when the oxidation is com-

plete, pouring the reaction mixture into water and separating the precipitate.

15. Process according to claim 14, wherein the cholanic acid is desoxycholic acid.

16. Process according to claim 14, wherein the amount of chromic oxide is approximately 77 g. in about 100 cc. of water.

17. Process according to claim 1, wherein the oxidizing agent comprises a mixture of chromic, acetic and sulfuric acids.

18. Process according to claim 1, wherein the oxidizing agent comprises a mixture of chromic, acetic and hydrochloric acids.

19. Process according to claim 1, wherein the acylating agent is acetic anhydride.

20. Process for the manufacture of nuclearily unsaturated steroid keto acids, which comprises brominating a nuclearily unsaturated 3,12-dihydroxy cholanic acid in the presence of an or-

ganic solvent base, reacting the brominated acid, dissolved in said base, with a sufficient amount of a carboxylic acid acylating agent to form the 3-ester, mixing the entire reaction solution with an oxidizing agent to effect replacement of the 12-hydroxyl with ketonic oxygen, and isolating the 12-keto acid either before or after debromination for effecting regeneration of the nuclear double bond.
